Filed June 19, 1958, Ser. No. 743,148

7 Claims. (Cl. 128—142)

This invention relates to a novel breathing system which is particularly useful in underwater swimming.

Heretofore, devices of this type have embodied an open system, i.e., a system wherein the diaphragm of the regulator means is exposed to the surrounding medium. This has produced serious difficulties in that it causes inadvertent operation of the control valves of the regulator due to the variations in the head of the surrounding medium applying pressure on the diaphragm. This results in inadvertent bleeding of air from the supply means. Also, since the diaphragm is exposed to the surrounding medium, particularly in the water, foreign matter, sand or the like carried by the water can move into contact with the diaphragm and damage the same. Further, such open systems produce variations in the breathing conditions for different attitudes of the swimmer since the changing head of water will affect the operation of the control means for supplying the air to the swimmer.

It is an object of the present invention to overcome these difficulties and to provide a closed self-balancing pressure system in the regulator controlled by the breathing cycle, with the inhalation pressure in the inhalation chamber and the exhalation pressure in the exhalation chamber acting upon respective sides of a regulator diaphragm in such a manner as to admit gas into the inhalation chamber from a supply under pressure to the extent necessary to automatically restore and maintain the desired balance. In this way there is eliminated breathing discomfort due to pressure differential as between inhalation and exhalation irrespective of the user's swimming attitude under water, while also precluding the bleeding out and escape of air from the supply due to a pressure differential on the diaphragm caused by the variations in the pressure thereon by the surrounding medium.

If desired, the exhaust valve means may be spaced from the regulator and disposed relative to the user's body in a locality adjacent to the human diaphragm. In this way, underwater breathing to fill the lungs is made relatively effortless and comfortable for the swimmer, because of the inhaling pressure and the exhaling pressure being rendered substantially equal at the reference level of the human diaphragm irrespective of the swimmer's attitude under water.

A feature of the present invention resides in the fact that the flexible diaphragm which divides the regulator casing into an inhalation pressure chamber is maintained out of contact with the surrounding fluid medium and in a dry condition and is well protected against damage as might occur from contact with the surrounding medium or contact with solid particles or sand that may become embedded in and produce pin holes or other damage to the diaphragm.

Other features and advantages of the invention will be apparent from the specification and claims when considered in connection with the accompanying drawings in which:

Figure 1 is a top view of the breathing apparatus of

2

this invention including the high pressure tank and the regulator unit with connections, with the parts positioned in the manner in which they are carried by the user.

Fig. 2 is a front view of the apparatus taken on line 5 2—2 of Fig. 1.

Fig. 3 is a greatly enlarged detail sectional view of the regulator, taken on line 3—3 of Fig. 1 showing the disposition of the diaphragm-controlled valve actuating mechanism as embodied in one form of the invention.

10 Fig. 4 is a schematic diagram of the closed system.

Fig. 5 shows a side view of the device carried by the user with the exhaust valve located adjacent the user's diaphragm.

Referring to Figs. 1, 2 and 3 of the accompanying drawings, the regulator according to this invention comprises a casing 10 divided by a diaphragm 11 to constitute an inhalation chamber 12 at one side of the diaphragm and an exhalation chamber 13 at the opposite side of the diaphragm as is customary in demand regulators.

20 Preferably, the casing 10 comprises a main casing shell 14 having a flange 14a and a complementary casing shell 15 formed with a flange 15a. The diaphragm 11 which may be formed of flexible impervious material, such as rubber or the like elastomeric material, is marginally 25 interposed between the flanges of casing shells and secured in airtight relationship therewith by means of a swedge ring 16 tightly encompassing and crimped around the flanges and the peripheral portion of the diaphragm interposed therebetween. The inhalation chamber has 30 mounted in it the control valve mechanism collectively designated I. While any control valve mechanism suitable for demand regulators may be used, in the illustrated form of the invention the control valve mechanism I has a valve housing V mounted in the casing 14 containing 35 the various control valves therein with valve actuating mechanism responsive to the movements of the diaphragm.

The regulator is detachably connected in a usual manner to the neck N of a tank 17 forming a supply of compressed breathable gas or air under high pressure by 40 means of a usual clamping shackle 18 screwed onto a nipple 19 fixed to the regulator casing by being screwed tightly into the valve housing V therein. A clamping screw 20 holds the shackle 18 in tight connection with neck N of the tank to provide the connection for high 45 pressure gas from the tank to the valve housing through the nipple and through the hand-operated valve 21 on the neck.

According to this invention, both the inhalation chamber and the exhalation chamber are connected to a 50 mouthpiece P through flexible hose connections 22 and 23 respectively, the exhalation chamber being moreover provided with a one-way exhaust valve 24 provided at the end of a flexible exhaust conduit 25 leading from the 55 exhalation chamber. In this way, there is established in the breathing apparatus of this invention a closed balanced pressure system having a single contact with the pressure of the surrounding fluid medium through the 60 normally closed exhalation valve 24 and in which system the inhalation pressure prevailing in the inhalation chamber is balanced against the exhalation pressure in the exhalation chamber, both pressures acting upon their 65 respective sides of the diaphragm. This will maintain the operation of the device constant in all attitudes of the user and also will prevent inadvertent bleeding of the supply. Since the regulator is out of contact with the surrounding medium, the diaphragm will be 70 protected against damage as may occur from sand or the like carried by the surrounding medium. With this balanced pressure a more sensitive regulator can be used and, further, the exhaust valve may be placed at any distance from the regulator proper without affecting the

normal operation of the device. Because of this I have found it desirable to locate the exhaust valve in a locality adjacent to the human diaphragm as illustrated at H in Fig. 5. In this way, the mechanism will maintain a balance between the inhalation pressure and the exhalation pressure at a value corresponding to the pressure of the surrounding fluid medium on the body in the area of the human diaphragm so that a maximum of breathing comfort may be afforded to the user which is unchanged irrespective of his swimming attitude under water.

As shown in Fig. 3, the control valve mechanism has mounted in the valve housing V thereof a primary control valve means operated by its primary actuating pin P_1 , and reserve valve means operated by its reserve actuating pin P_2 , controlling the flow of gas from the tank to the inhalation chamber. The control mechanism for the valves includes a pair of valve actuators 26 and 27 for cooperating with the primary and the reserve valve actuator pins respectively, said valve actuator having a pivotal connection 26a and 27a respectively with the valve housing V. The actuators are swingable towards and away with respect to each other for sequentially engaging and operating the respective control valve means by depressing their respective actuating pins in response to pressure variations in the inhalation chamber 12 and the concurrent movements of the diaphragm, admitting air from the tank into the inhalation chamber 12 to provide the required pressure therein.

The two swingable valve actuators 26 and 27 have their outer ends pivotally connected at 26b and 27b to a pair of actuating links or plates 28 and 29 respectively. The links or plates are pivotally interconnected as by a hinge connection 30, and they are in turn fastened to the diaphragm 11 so that a ridge R is formed therebetween which is adapted to rise and fall within the limits allowed for by reserve mechanism M as the included angle A between the plate varies in response to pressure variation in the inhalation chamber.

In the illustrated form of the invention the reserve mechanism M is located in the exhalation chamber and comprises a shaft 31 journaled in the wall of the complementary shell 15 in airtight relationship therewith. A stop member 32 extends from the diaphragm in cooperative relationship with the shaft. The shaft has a recessed abutment face 33 normally positioned in the manner shown to face away from the stop member 32 so that the movement of the diaphragm is normally limited by the stop member engaging the shaft at its periphery during the normal operation of the primary control valve means.

But when the pressure in the tank falls below the normal operating value, the shaft is rotated as by manipulating the actuating rod 34 linked to a crank arm 35 fixed to the outer face end of the shaft and the recessed abutment face 33 will attain a position relative to the stop member to allow extra movement of the diaphragm in response to pressure variation in the inhalation chamber 12. This will cause the actuator 27 to depress the reserve valve operating pin P_2 to admit reserve air providing normal reserve pressure in the inhalation chamber, after the normal supply through the primary control valve will have ceased.

Flushing of the inhalation chamber 12 and of the inhalation tube 22 and mouthpiece P may be effected at will by rotating the shaft 31 of the reserve mechanism so that a flush finger F extending radially from the shaft will engage and depress the diaphragm against the normal breathing pressure and actuate the valve means to admit flushing air into the chamber 12.

The operation of the system according to this invention is well illustrated in Figs. 4 and 5.

Fig. 4 illustrates the breathing cycle particularly with respect to showing how the inhalation pressure and the exhalation pressure are balanced one against the other,

with the diaphragm itself kept dry between the two operating chambers 12 and 13 and thus sealed within the closed system against the surrounding medium when submerged.

The operation of the breathing cycle illustrated in Fig. 4 comprises inhaling air from chamber 12 through check valve V_1 (see arrow W_1) with the concurrent slight pressure drop in that chamber causing the diaphragm 11 to move the valve actuator 26 to actuate the primary valve actuating pin to admit the air needed to maintain the normal breathing pressure in this chamber. This movement of the diaphragm is aided by the pressure in the exhaust chamber caused by the exhaust flap valve 24, when collapsing, reducing the volume of the gas trapped in the exhalation chamber with both the check valve V_2 and the exhaust valve 24 remaining closed.

Next, when exhaling through the mouthpiece (see arrow W_2) against a pressure determined by the location of the exhaust valve 24 relative to the regulator and relative to the person of the user (as exemplified in Fig. 5), the corresponding exhaling pressure will act upon the diaphragm 11 depressing the same to admit air through the concurrent operation of the control valve mechanism I until the pressure in that chamber equals the exhalation pressure at the opposite side of the diaphragm. The diaphragm thereby recedes again towards the exhalation chamber stopping further inflow of air into the inhalation chamber at the point when equilibrium is substantially attained as between the pressures acting upon the respective sides of the diaphragm.

Variations and modifications may be made within the scope of the claims and portions of the improvements may be used without others.

I claim:

1. A regulator for breathable gases comprising a pair of shells closed by diaphragm means to constitute an inhalation chamber and an exhalation chamber respectively, said diaphragm means being adapted to move in response to a differential between inhalation pressure and exhalation pressure in the respective chambers, said inhalation chamber having an inhaling connection leading therefrom to a mouthpiece and a supply connection leading thereto from a source of gas under pressure, control valve means with actuating mechanism disposed in the inhalation chamber and controlled by the movement of the diaphragm to admit breathable gas from said source into said inhalation chamber until the pressures in said chambers are substantially equal, and exhaling conduit means from said mouthpiece communicating with said exhalation chamber and provided with a one-way exhaust valve means adapted to discharge spent gas into the surrounding medium.

2. A regulator for breathable gases, comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connection leading thereto from a source of gas under pressure, control valve means with actuating mechanism disposed in the inhalation chamber and controlled by the movement of the diaphragm to admit breathable gas from said source into said inhalation chamber until the operating pressure in the inhalation chamber and the pressure in the exhalation chamber are substantially equal, and exhaling conduit means from said mouthpiece communicating with said exhalation chamber and provided with a one-way exhaust valve means adapted to discharge spent gas into the surrounding medium.

3. A regulator for breathable gases, comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connec-

tion leading thereto from a source of gas under pressure, control valve means with actuating mechanism disposed in the inhalation chamber and controlled by the movement of the diaphragm to admit breathable gas from said source into said inhalation chamber until the operating pressure in the inhalation chamber is substantially equal to the pressure in the exhalation chamber and exhaling conduit means from said mouthpiece communicating with said exhalation chamber and provided with a one-way exhaust valve means adapted to discharge spent gas into the surrounding medium, said exhaling conduit means comprising a first conduit portion between the mouthpiece to the exhalation chamber and a second conduit portion between said chamber and said exhaust valve means.

4. A regulator for breathable gases, comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connection leading thereto, from a source of gas under pressure, control valve means with actuating mechanism disposed in the inhalation chamber and controlled by the movement of the diaphragm to admit breathable gas from said source into said inhalation chamber until the operating pressure in the inhalation chamber is substantially equal to the pressure in the exhalation chamber and exhaling conduit means from said mouthpiece communicating with said exhalation chamber and provided with a one-way exhaust valve means adapted to discharge spent gas into the surrounding medium, and reserve mechanism and high pressure flushing means provided in said exhalation chamber.

5. A regulator for breathable gases comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connection leading thereto from a portable container holding the gas under pressure and having the regulator associated therewith, control valve means with actuating mechanism disposed in the inhalation chamber and controlled by the movement of the diaphragm to admit breathable gas from said source into said inhalation chamber until the operating pressure in the inhalation chamber is substantially equal to the pressure in the exhalation chamber and exhaling conduit means from said mouthpiece communicating with said exhalation chamber and provided with a one-way exhaust valve means adapted to dis-

charge spent gas into the surrounding medium, and means for placing the exhaust valve means relative to the user's body to be located adjacent to the human diaphragm.

6. A regulator for breathable gases, comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connection leading thereto, from a portable container holding the gas under pressure to be carried on the user's back and having the regulator associated therewith, control valve means with actuating mechanism disposed in the inhalation chamber and controlled by the movement of the diaphragm to admit breathable gas from said source into said inhalation chamber until the operating pressure in the inhalation chamber is substantially equal to the pressure in the exhalation chamber and exhaling conduit means from said mouthpiece communicating with said exhalation chamber and provided with a one-way exhaust valve means adapted to discharge spent gas into the surrounding medium, and means for fastening the exhaust valve means to said container and spaced from said regulator.
- 10 7. A regulator for breathable gases, comprising a casing, a movable diaphragm dividing the casing into an inhalation chamber and an exhalation chamber sealed against each other and against the surrounding medium, said inhalation chamber having an inhaling connection leading therefrom to a mouthpiece and a supply connection leading thereto, from a portable container holding the gas under pressure to be carried on the user's back and having the regulator associated therewith at the top thereof, control valve means with actuating mechanism disposed in the inhalation chamber and controlled by the movement of the diaphragm to admit breathable gas from said source into said inhalation chamber until the operating pressure in the inhalation chamber is substantially equal to the pressure in the exhalation chamber, exhaling conduit means from said mouthpiece communicating with said exhalation chamber and provided with a one-way exhaust valve means adapted to discharge spent air into the surrounding medium, and means for fastening the exhaust valve means to the container spaced from said regulator as well as relative to the user's body adjacent to the human diaphragm.
